UNITED STATES PATENT OFFICE

PATRICK WALL, OF ITHACA, NEW YORK.

TOE-SPREADING RETAINER.

No. 853,327.

Specification of Letters Patent.

Patented May 14, 1907.

Application filed May 7, 1906. Serial No. 315,485.

To all whom it may concern:

Be it known that I, PATRICK WALL, a citizen of the United States, residing at Ithaca, in the county of Tompkins and State of New York, have invented certain new and useful Improvements in Toe-Spreading Retainers, of which the following is a specification.

My invention relates to a device for the straightening of toes and the curing of bunions on the human foot and more particularly to a device adapted to be placed inside of the stocking and shoe when worn on the foot, for the purpose of curing deformities of the foot, caused by wearing improperly fitting shoes.

The object of my invention is to provide a device that can be worn with comfort by persons desiring for any reason to normally retain the toes in separated relations; this is highly desirable in the case of corns, bunions, ingrowing toe-nails, over and under-lapping toes, as such separation not only affords relief but also an opportunity for growth to the normal position and a permanent cure resulting therefrom. In the case of a bunion, for example, upon the metatarsophalangeal great-toe-joint, the great-toe being pressed upon by the shoe is forced inward and said joint outward, thus tending to cripple the toe for use in walking and forcing it under or over its neighbor; relief may be afforded by spreading the over-lapped toes, which restores the toe to its natural position and reduces the joint.

A further object is to provide such a device that yields to the movements of the foot in walking and running and employs no metallic or other non-yielding substance possible of injury to the foot in case of accident.

The devices now in use are inconvenient and uncomfortable to wear and it is now intended to provide such a device for carrying out the said desired functions and advantages that is exceedingly simple and cheap to manufacture and which at the same time is of small weight and size, yet durable, and perfectly accomplishes the objects set forth.

With these general objects in view, and others, which will appear as the nature of the improvement is better understood, the invention consists, substantially, in the novel construction, combination and arrangement of parts, which will be hereinafter fully described, illustrated in the accompanying drawings, and pointed out in the appended claims.

While the forms of the invention herein shown and described are what are believed to be preferable embodiments thereof, it is to be understood that the same are susceptible of various changes in the form, proportion and minor details of construction, and the right is therefore reserved to modify or vary the invention as falls within the spirit and scope thereof.

In the drawings forming a part of this specification and in which the same characters of reference designate similar parts through the several views, Figure 1: represents a human foot, showing my device as designed for use in position between the toes. Fig. 2: is a perspective view of my device. Fig. 3: a perspective view of a modified form using but a single tube. Fig. 3^a is a similar view of a further modification showing the single tube construction provided with a top pad. Fig. 4: is a top plan view of Fig. 2. Fig. 5: is a sectional view taken upon line X—X of Fig. 4, but showing both tubes filled with cotton. Fig. 6: is a top plan view of a modified form of my invention. Fig. 7: is a sectional view of Fig. 6, taken upon the line Y—Y.

Referring in detail to the drawings, the numeral 1 designates a human foot, having five toes or digits, numbered respectively from the great-toe 2, 3, 4, 5 and 6,—the great-toe being designated as 2. A bunion 7 is shown upon the metatarsophalangeal great-toe-joint, and my device is shown in position, a portion of the same being in dotted lines, between said great-toe 2 and its neighbor, the second digit, designated 3.

The device is preferably molded out of pliable rubber and embraces a thin perforated oval-shaped base pad 9, having a hollow tube 10 (Figs. 3, 3^a) or two hollow tubes 10 and 11 (Figs. 2, 4 to 7) mounted thereon and incircling these perforations. The pad 9 is worn under the foot and is of any desired area, the weight of the foot thereupon holding the device in position.

When properly placed the tube 10 or tubes 10 and 11 hold the toes separated, one from another, and said tube or tubes may be given further rigidity by filling the same with cotton as indicated by 12 in Fig. 5. For use between the 4th. digit and the 5th. or little toe, I preferably use the forms shown in Figs. 3, 3^a employing but one tube, such as 10 upon the smaller pad 9.

That the device may not slip out of place, I

may employ a second and smaller pad secured to the tops of the tubes 10 and 11, shown in Fig. 6 and designated as 13 and being parallel to the lower pad 9.

5 Fig. 3^a shows the employment of the upper pad in connection with a single tube.

To furnish the device having different degrees of rigidity, my invention may be made of different kinds of rubber and also of different materials, the tubes may be filled with suitable matter, and, as shown in Fig. 6 the ends of the tubes may be sealed, changing the same into pneumatic cushions. One or more tubes may be employed, preferably in 10 parallel relation to each other and perpendicular to the supporting pad 9.

In the case of a bunion, where the great-toe has been forced under or over the second digit, bending the great-toe joint in such a 15 manner as to make it less effective in walking, my device, when placed as shown between the first and second toes prevents any over or under-lapping, it forces the first digit back to its natural position for use in walking, and 20 by forcing the toe outward the metatarsophalangeal great-toe-joint is forced inward. The said joint being returned to its normal position as described, reduces the bunion on the same. The said joint and the bunion 25 thereon, then come less in contact with the pressure of the shoe and by holding the toe securely in its natural position, relief and a cure is effected. In a similar manner my device may be used between any two toes 30 and in case of in-growing toe-nails, it pre-

vents the toes contacting and rubbing together, thus preventing further ingrowth from pressure.

Having thus described my invention and in what manner the same is to be used, what I claim as new and desire to secure by Letters Patent of the United States, is,

1. The herein described article, comprising a perforated flexible base-pad, and a flexible tube mounted on the pad and encircling the perforation at right angles to the face of the base-pad. 45

2. The herein described article, comprising a perforated base-pad, and one or more upwardly-projecting flexible tubes encircling the perforation or perforations of said pad. 50

3. The herein described article, comprising a flexible base-pad, and a flexible tube integral therewith and projecting upwardly therefrom at right angles to the face of the pad. 55

4. The herein described article, comprising a flexible base-pad, one or more flexible tubes integral therewith and projecting upwardly at right angles to the face of the pad, and a top or cover pad for said tube or tubes, the top or cover pad being parallel with the base-pad. 60

In testimony whereof I affix my signature in presence of two witnesses.

PATRICK WALL.
